UNITED STATES PATENT OFFICE.

EDWARD S. COLE, OF UPPER MONTCLAIR, NEW JERSEY

RECORDING DEVICE.

No. 880,720.

Specification of Letters Patent.

Patented March 2, 1908.

Application filed February 17, 1904. Serial No. 193,937.

To all whom it may concern:

Be it known that I, EDWARD S. COLE, a citizen of the United States, residing at Upper Montclair, in the county of Essex and State 5 of New Jersey, have invented a certain new and useful Improvement in Recording Devices, of which the following is a full, clear, concise, and exact description, reference being had to the accompanying drawings, 10 forming a part of this specification.

My invention relates to devices for recording the velocity and static pressure of flowing streams.

The principal object of the invention is to 15 provide a simple, practical and inexpensive device of the class specified, and to particularly avoid friction therein and thereby secure accuracy in the recording operation.

In the accompanying drawings, Figure 1 20 is a view partly diagrammatic and partly in vertical section, of a recording device embodying my invention; Figs. 2 and 3 are views of a portion of the device, in different modified forms.

In Fig. 1, A represents a pipe or main in 25 which flows the stream whose velocity and pressure are to be recorded. This can be a water main or water pipe or other pipe of various kinds. A pair of tubes 1 and 2 are 30 extended from the pipe A. Both tubes extend down into the pipe. The tube 1 has a bent end 3 which faces the flowing stream, and the tube 2 has a bent end 4 which is turned in the opposite direction. These 35 tubes 1 and 2 extend to a structure B made in the form of a U-tube, and to such end comprising vertical tubular sections 5 and 6 connected with one another by a horizontally extending section 7. This U-tube B is provided at its lower end with a heavy liquid 8, the upper portion being filled with water 40 communicating with the main A. The section 6 is slotted at one side, and to this side is secured a strip 9 of insulating material 45 which closes the slot and is provided with a series of contacts 10, 10. A float 11 is confined in the section 6, and is provided with wheels or rollers 12, 12 and 13, 13 at its lower and upper ends respectively. The 50 float 11 is so constructed and balanced that it will rise and fall in accordance with the variations in the height of the heavy liquid 8 which can be mercury or other liquid.

C is a rotary drum on which is arranged a 55 sheet of paper on which the record is to be kept. This drum is associated with a clock

mechanism 14 by which it can be slowly turned. A series of pencils 15, 15 is mounted in the end of a series of fingers 16, 16, so that the pencils are arranged in position in series, 60 lengthwise of the drum. The fingers 16, 16 are parts or extensions of armatures 17, 17 pivoted at 18, 18. Below the armatures 17, 17 are electro-magnets 19, 19 which are connected with wires or conductors 20, 20 extending to the contacts 10, 10 on the leg 6 of the tube B. The magnets 19, 19 are also connected with a conductor 21 which extends to a battery 22 and thence is connected with the leg 6. A pressure gage D is connected 70 by a tube 23 with the main A. The pressure gage D is provided with a swinging arm or hand 24 carrying a pencil 25 which is arranged to work upon the paper on the drum C. The upper pencils 15, 15 are nearer together than the lower ones and the difference between them increases from top to bottom.

The operation of the device is as follows. The liquid flowing in the main or conduit A causes a displacement of the heavy liquid 8 in the tube B by reason of the fact that the velocity pressure is exerted against the bent end of the tube 1 and not against the bent end of the tube 2. The displacement of this heavy liquid occurs as shown in the figure, the liquid in the leg 6 rising above that in the leg 5. This displacement varies of course in accordance with the velocity of the stream. As the liquid varies, the float 11 is raised or lowered accordingly. Its changes in position cause one of the wheels 13 to make connection with various ones of the contacts 10, 10, and thereby complete the circuits through different ones of the magnets 19, 19. As these magnets are energized they attract 85 their armatures 17, 17, and cause the pencils 16, 16 to come in contact with the paper on the drum C, which in its rotation causes corresponding marks to be made on the paper. As the float rises, the upper magnets 100 are energized and marks are made by the upper pencils, and as the float descends, the lower magnets are energized and marks made by the lower pencils. Thus marks are made in accordance with the variations in the level 105 of the heavy liquid in the leg 6 and thus in accordance with variations in the velocity of the stream flowing in the pipe A. By varying the distance between the pencils, I compensate for the varying height which the 110 float rises for equal increments of velocity, as the flow increases from a low to a high

rate. The advantage of this is that the record has equal ordinates drawn from the base line for equal increments of velocity in the main. For instance, each inch vertically 5 may represent one foot per second velocity in the main. The record produced may thus be integrated with a planimeter. The hand 24 is swung in accordance with the variations in static pressure in the main A, and thus a 10 record is kept of this static pressure. Thus the device keeps an accurate record of both the velocity and static pressures of the liquid flowing in the main or conduit.

In Fig. 2 I have shown the cylinder C with 15 a typewriter ribbon 27 interposed between it and the pencils 15, 15. In such case the latter of course can be made merely metal or similar points without any lead such as lead pencils have.

20 In Fig. 3 I have shown the cylinder and a pen 28 which is one of a row of pens employed instead of the pencils 15, 15 for making a record on the record sheet. These pens can be of any suitable or desired construction 25 adapted to operate in the arrangement shown.

Changes and modifications may be made in the device herein set forth, without departing from the spirit of the invention.

30 What I claim is:—

1. The combination with a main or conduit for the flowing stream, of tubes 1 and 2 connected therewith, a U-tube B containing a heavy liquid, a float in one of the legs of 35 said U-tube, electrical contacts along the side of said leg, conductors extending from said contacts, magnets to which said conductors are connected, pencils carried by the armatures of said magnets, a rotary drum

associated with said pencils, and means for 40 rotating said drum substantially as described.

2. In a device of the class specified, the combination of a series of recording devices separated from one another by varying distances which are computed to indicate desired units of velocity, and means controlled by a flowing stream for actuating said devices, substantially as described.

3. In a device of the class specified, a rotary drum, a series of pencils arranged lengthwise of the axle of said drum and separated from one another by increasing distances which are computed to indicate like units of velocity, a series of electromagnets 55 for operating said pencils, and means controlled by a flowing stream for energizing said magnets.

4. An apparatus of the class specified, comprising a conduit for the flowing stream, 60 tubes 1 and 2 connected therewith, a U-tube containing a float, a series of electromagnetic devices provided with connections by which they are operated by said float, a series of pencils operated by said electromagnetic devices, a rotary drum associated with said pencils, and a pressure gage connected with the tube 2 and having an arm 24 provided with a pencil 25 adapted for use in connection with the rotary drum, substantially as 65 described.

In witness whereof, I hereunto subscribe my name this 8th day of February, A. D., 1904.

EDW. S. COLE.
